(57) CLAIM

The ornamental design for a propeller with half safety ring, as shown and described.

DESCRIPTION

FIG. 1 is a right front perspective view showing the new design;

FIG. 2 is a right side elevational view thereof;

FIG. 3 is a top view thereof;

FIG. 4 is a bottom view thereof;

FIG. 5 is a front side view thereof, the front view being the same;

FIG. 6 is a right side view thereof; and,

FIG. 7 is a left side view thereof.

The broken lines shown in the drawings show environmental structure and are for illustrative purposes only and form no part of the claimed design.
